CONCENTRATOR

Waller C. Hudson, Helen, Ga.

Application October 1, 1940, Serial No. 359,287

14 Claims. (Cl. 209—458)

The invention relates particularly to a concentrator or separating device and is especially adapted for separating particles of material carried by a liquid stream or current. The device is intended to operate on the heavier particles and separate them from the stream carrying the lighter particles which may pass on to waste or further treatment. There are many industrial uses for such a device. Specific and important uses are in the treatment of mined material. Thus a stream of water carrying solids of different specific gravities may be treated by the present invention to concentrate or separate the heavier and generally more valuable solids, including such materials as flour gold from saprolite or sand, and metals from their gangue, etc.

It has been found that liquid carrying solids when passed at proper rates of flow through a curved channel tends to collect or concentrate the heavier particles at certain points in the path of travel. When a current impinges against a concave curve there is a tendency for the solid particles carried to concentrate close to the curved wall. When the current leaves the concave point in the wall it spreads across the channel and tends to throw the heavier particles or concentrate more or less directly toward the other side of the channel, their course varying with the character of the liquid, the speed of flow and with the weight of the specific particles being carried. In order to take practical advantage of this operation it may be desirable or necessary to confine the flow of liquid to a relatively narrow channel. In order to concentrate the main part at least of the heavier particles the channel may be sinusoidal or made up of a plurality of succeeding reverse curves. A few curves in the channel may be sufficient and they may be all included in a relatively short run or length of channel. In order to handle a larger quantity of material it may then be desirable to assemble a plurality of the relatively small channels which may thus produce separation or concentration of a sufficient amount of material to make the operation commercially practicable.

In order to take advantage of the fact that a stream of liquid carrying solids of different gravities and flowing around a curve so as to deposit the heaviest solids in a restricted area of the stream bed it may be desirable to decrease the velocity of the stream of liquid carrying such solids of different specific gravities at appropriate points so as to aid in such deposit of the heaviest solids. This may be accomplished by

means of appropriately placed and positioned baffles or riffles associated with which may be provided openings in the bottom of the channel through which may be dropped and removed the heavier particles, separation and saving of which may be specially desirable.

For the best procedure with a specific material it may be desirable to have a carefully designed structure in which the form and proportions are carefully designed so as to most effectively cooperate with the liquid at the most effective speed but such a specific, refined arrangement may not be necessary for carrying out the invention which may produce desirable results in many forms and proportions.

In the accompanying drawing, for the purpose of illustrating the invention but without limiting it, is shown one specific form of apparatus which is especially adapted to the separation of such material as flour gold from saprolite or sand. Figure 1 is a more or less diagrammatic plan view of a pair of concentrating channels enclosed in an outer casing. Fig. 2 is a side elevation of the apparatus. Fig. 3 is an enlarged fragmentary plan view showing details of form. Fig. 4 is an enlarged fragmentary cross section on the line 4—4 of Fig. 1.

As illustrated the device may consist of an outer casing 10 which may be a sheet of metal turned up at its sides to make side walls 11 as shown in Fig. 4. For convenience the side walls 11 may be straight or of any desirable form. Mounted within the side walls 11 are shown three longitudinal wall members, 12, 13, 14 forming between them two channels through which the liquid may pass for concentration. The walls 12, 13, 14 are each curved but are soldered or otherwise mounted on the bottom substantially parallel to each other so that the channel 15 between the walls 12 and 13 is preferably of substantially the same width throughout its length and the channel 16 between the walls 13 and 14 is preferably of substantially the same width throughout its length. As illustrated each channel and its walls are made up of a succession of reversed curves. Thus the channel beginning at the left in Fig. 1 makes a curve toward the bottom at 17 immediately followed by a curve toward the top at 18 and so on throughout the length of the channel. There are illustrated four of these double curves which may be a suitable number for practical operation, although any other number may be chosen and employed.

It will be seen, thus, that each wall of the

channel consists of a succession of convex and concave curves, there being opposite the convex curve on each wall a corresponding concave curve on the opposite wall. The terms concave and convex are employed here with respect to the middle of the channel. Thus the curve at 17 in the upper wall illustrated in Fig. 1 is a convex curve while the curve at 18 in the upper wall is a concave curve. It will be understood that liquid in passing from left to right for instance in Fig. 1 through the channel made up of succeeding reverse curves will constantly have its direction changed and when the direction is changed the tendency will be to concentrate and position at least the heavier solid particles carried by the liquid. In order to take advantage of this arrangement and positioning riffles or baffles 19 may be appropriately placed so as to be in the path of the portion of the liquid carrying the heavier particles. As heavier particles thus impinge upon the riffle or baffle their speed will be stopped or reduced and they may be deposited on the bottom of the channel. Each baffle 19 may be curved so as to present a convex surface to the material flowing over or against it. This arrangement tends to cause the heavier particles to deposit and also tends to not fill up or dam the channel but to allow the unseparated material to pass onward. Preferably at the down stream portion on the convex side of the baffles 19 there may be provided openings or holes 20 in the bottom of the channel through which the impeded or settled heavier portions of the solid carried by the liquid may pass into a trough, pan or launder 21 which as is illustrated in Fig. 2 may be placed immediately under the trough 10.

As illustrated in Fig. 2, in order to aid in the operation of the device and the passage of the liquid and the recovered material the trough 10 and the trough 21 may both be mounted on bases so as to incline downwardly from the left hand end to the right hand end, that is, in the direction of flow of the laden liquid. This will tend to aid the free flow of the liquid bearing the solid through the trough 10 and may aid in the collection and removal of the heavier particles from the trough 21. The angle at which the troughs are mounted is not essential to the present invention although in the specific apparatus to be described in detail it has been found that an angle or grade of about 10% is suitable and may be desired.

In one specific construction in which the trough is set at a 10% grade there has been satisfactorily treated a liquid carrying 15% to 20% solids at a speed of about 8 gallons per minute. Such a structure may be about 10 feet long, in which arrangement the successive concave curves in the channels may be about 30 inches apart. The width of each channel may be about four inches and the height of the side walls may be about two inches. The concave and the convex curvature of the side walls may be symmetrical and both may be formed with a radius of about $15\frac{1}{8}$ inches, it being noticed that this radius is nearly four times the width of the channel. With this arrangement all the succeeding curves on opposite sides of the channel such as those marked A B and C in Fig. 3 may have a common tangent. Thus the same line which would be tangent to the curve at C would also be tangent to the curve at B and the curve at A etc. By such an arrangement the curvature of the sides and the width of the box are so interrelated that the concentra-

tion of the heavier solids caused first by the liquid going round a curve and second by the decrease in the velocity of the stream occurs at the same time and place, thus causing a maximum concentration of the heavier solids in a minimum restricted area. The operation with this arrangement is shown diagrammatically in Fig. 3 where it will be seen, for instance, that the flow is such that substantially all of the solid particles carried by the liquid are concentrated in the concave curve above A for instance and from there the particles spread, the heavier particles going to the lower portion of the dotted outline. The carried particles are then again collected and forced against the concave curve below B, for instance, from which they pass and spread so that the heavier particles are at the upper portion of the dotted area as they pass on to be collected again at the concave wall above C and so on through the entire course of the channel. In order to take advantage of this effect there are placed in the bottom of the channel at the proper points to engage the heavier particles carried by the liquid, curved riffles or baffles 19. In a channel of the size indicated above these riffles may be flat strips fastened to the bottom of the channels of about $\frac{1}{4}$ of an inch wide and about $\frac{3}{8}$ of an inch thick. The riffles are preferably curved on a radius of about $7\frac{1}{2}$ inches which is about half the radius of the curves making up the sides of the channels. The arc of the outer edge of the riffles is about $9\frac{1}{2}$ inches and it is found convenient to arrange these riffles with their convex surfaces directed upstream and placed so that they may receive the heavier particles of the solid material carried by the liquid in such a way that the particles may tend to be retarded and deposit and roll more slowly forward along the riffles. To this end each riffle may be attached to the bottom so that its end abuts against the convex wall slightly in advance of the peak, or at about $1\frac{3}{4}$ inches to the right of the curve peak A as indicated in Fig. 3. The forward end of the riffle then will be about $4\frac{1}{4}$ inches to the left of the radius passing through the peak of the curve B, and it may preferably be arranged so that its foremost corner is vertically two inches below the line which would be tangent to the curve B as illustrated in Fig. 3. In this arrangement it may be convenient and efficient to provide small holes in the bottom of the trough immediately adjacent the down stream edge of the riffle extending backward along the arc a little less than half of its length. One satisfactory arrangement consists of four of these holes, one placed about a quarter of an inch back from the down stream end of the riffle and the other three placed at intervals of about $1\frac{1}{4}$ inches therefrom. By this arrangement it will be seen that as the liquid carrying solids passes through the trough there is a tendency for the heavier particles to arrange themselves more or less along the lines D, E and F, G etc. As these heavier particles move forward a considerable portion of them impinges on the baffles and is directed along the edge of the baffle more or less along the lines D, H and F, K etc. Thus at each baffle a considerable portion of the heavier particles are influenced to progress more slowly along the edge of the riffle and fall through the holes 20 into the launder 21. The curved shape of the riffle and its location in respect to the restricted concentration area causes a maximum of heavier solids and a mini-

mum of lighter ones to be deflected along the convex side of the riffle over the discharge holes arranged around its down stream portion.

I claim as my invention:

1. A concentrator comprising a trough having substantially parallel walls formed with succeeding reversed curves the curves being on radii approximately four times the width of the trough.

2. A concentrator comprising a trough having a bottom and substantially parallel side walls formed with succeeding reversed curves, curved baffles extending from convex portions of the walls in the path of the heaviest particles passing through the concentrator, and perforations in the bottom of the concentrator adjacent the baffles.

3. A concentrator comprising a trough having a bottom and substantially parallel side walls formed with succeeding reversed curves, the curves being on radii approximately four times the width of the trough, curved baffles in the path of the heaviest particles passing through the concentrator the baffles being curved on radii approximately one half the radii of the wall curves and presenting their convex sides to the stream, and perforations in the bottom of the concentrator adjacent the baffles.

4. A concentrator comprising a trough having a bottom and substantially parallel side walls formed with succeeding reversed curves the curves being on radii approximately four times the width of the trough, curved baffles in the path of the heaviest particles passing through the concentrator and presenting their convex sides to the stream, and perforations in the bottom of the concentrator adjacent the baffles.

5. A concentrator comprising a trough having a bottom and substantially parallel side walls formed with succeeding reversed curves, curved baffles in the path of the heaviest particles passing through the concentrator the baffles being curved on radii approximately one half the radii of the wall curves and presenting their convex sides to the stream, and perforations in the bottom of the concentrator adjacent the baffles.

6. A concentrator comprising a trough having a bottom and side walls formed with succeeding reverse curves each on a radius approximately four times the width of the trough with the convex curves on opposite walls having a common tangent, reversely curved baffles in the path of the heaviest particles and presenting their convex sides to the stream, and perforations in the bottom of the concentrator adjacent the down stream ends of the convex sides of the baffles.

7. A concentrator comprising a trough having a bottom and side walls formed with succeeding reverse curves each on a radius approximately four times the width of the trough with the convex curves on opposite walls having a common tangent, reversely curved baffles in the path of the heaviest particles the baffles being curved

on radii approximately one half the radii of the wall curves and presenting their convex sides to the stream, and perforations in the bottom of the concentrator adjacent the down stream ends of the convex sides of the baffles.

8. A concentrator comprising a trough having a bottom and side walls formed with succeeding reverse curves the convex curves on opposite walls having a common tangent, reversely curved baffles in the path of the heaviest particles the baffles being curved on radii approximately one half the radii of the wall curves and presenting their convex sides to the stream, and perforations in the bottom of the concentrator adjacent the down stream ends of the convex sides of the baffles.

9. A concentrator comprising a trough having a bottom and side walls formed with succeeding reverse curves the convex curves on opposite walls having a common tangent, reversely curved baffles in the path of the heaviest particles and presenting their convex sides to the stream and perforations in the bottom of the concentrator adjacent the down stream ends of the convex sides of the baffles.

10. A concentrator comprising a trough having a bottom and side walls formed with succeeding reverse curves the convex curves on opposite walls having a common tangent, baffles in the path of the heaviest particles, and perforations in the bottom of the concentrator adjacent the baffles.

11. A concentrator comprising a trough having substantially parallel side walls formed with succeeding adjacent substantially similar reversed curves, a substantially smooth bottom for the trough having perforations therein, and baffles on the bottom adjacent the downstream sides of the perforations.

12. A concentrator comprising a trough having a bottom and substantially parallel side walls in contact with the bottom and formed with succeeding reversed curves the degree of curvature being sufficient to deflect the flow of the heaviest particles toward the next succeeding concave side of the opposite wall, and baffles in the paths of the heaviest particles passing through the concentrator.

13. A concentrator comprising a trough having a bottom and substantially parallel side walls in contact with the bottom and formed with succeeding longitudinal reversed curves, the succeeding convex curves on opposite side walls having a substantially common tangent.

14. A concentrator comprising a trough having a bottom and substantially parallel side walls in contact with the bottom and formed with succeeding, substantially similar, longitudinal reversed curves, the succeeding convex curves on opposite side walls having a substantially common tangent.

WALLER C. HUDSON.
